United States Patent Office.

THOMAS DOLAN, OF PHILADELPHIA, PENNSYLVANIA.

Design No. 3,352, dated January 26, 1869.

DESIGN FOR A STOCKING-FABRIC.

The Schedule referred to in these Letters Patent and making part of the same.

To all whom it may concern:

Be it known that I, THOMAS DOLAN, of the city and county of Philadelphia, State of Pennsylvania, have originated a new Design for a Stocking-Fabric; and I do hereby declare that the accompanying drawing, and following explanation thereof, form a full, clear, and exact description of the said design.

In the drawing, the figure represents sufficient of a stocking-fabric to illustrate the design, the most prominent features of which are the two patterns, *A A*, and between the latter are the two zigzag stripes, *b b*.

Each pattern *A* consists of a combination of zigzag

stripes, the arrangement of which is clearly shown in the drawing.

Irrespective of the colors employed,

I claim the design for a stocking-fabric, substantially as described, and represented in and by the accompanying drawing.

In testimony whereof, I have signed my name to this specification, in the presence of two subscribing witnesses.

Witnesses:

THOMAS DOLAN.

CHAS. H. SALMON,

CLINTON M. LATOURETTE.
